CLAIM

The ornamental design for a combined toilet and wash basin unit, as shown.

DESCRIPTION

FIG. 1 is a perspective view taken from the top, front and left side of a combined toilet and wash basin unit showing my new design;

FIG. 2 is a right side elevational view thereof;

FIG. 3 is a top plan view thereof;

FIG. 4 is a front elevational view thereof;

FIG. 5 is a perspective view taken from the top, front and left side of a modified form of the combined toilet and wash basin unit shown in FIG. 1;

FIG. 6 is a right side elevational view of FIG. 5;

FIG. 7 is a top plan view of FIG. 5;

FIG. 8 is a front elevational view of FIG. 5;

FIG. 9 is a perspective view taken from the top, front and left side of a second modified form of the combined toilet and wash basin unit shown in FIG. 1;

FIG. 10 is a right side elevational view of FIG. 9;

FIG. 11 is a top plan view of FIG. 9;

FIG. 12 is a front elevational view of FIG. 9;

FIG. 13 is a perspective view taken from the top, front and left side of a third modified form of the combined toilet and wash basin unit shown in FIG. 1;

FIG. 14 is a right side elevational view of FIG. 13;

FIG. 15 is a top plan view of FIG. 13; and

FIG. 16 is a front elevational view of FIG. 13.

FIG. 1.

FIG. 2.

FIG. 3.

FIG. 4.

FIG. 5.

FIG. 6.

FIG. 8.

FIG. 9.

FIG. 10.

FIG. 12.

FIG. 13.

FIG. 14.

FIG. 16.
